UNITED STATES PATENT OFFICE.

JOSEPH E. MARTIN, OF KANSAS CITY, MISSOURI, ASSIGNOR TO THE BRYANT ELECTRIC COMPANY, OF BRIDGEPORT, CONNECTICUT, A CORPORATION OF CONNECTICUT.

GLOBE-HOLDER.

1,029,384.

Specification of Letters Patent. Patented June 11, 1912.

Application filed January 20, 1912. Serial No. 672,295.

To all whom it may concern:

Be it known that I, JOSEPH E. MARTIN, a citizen of the United States of America, residing in Kansas City, in the county of

5 Jackson and State of Missouri, have invented certain new and useful Improvements in Globe-Holders, of which the following is a specification.

10 My invention relates to an improvement upon the construction of globe supports or shade holders for gas and electric lamps and the like, forming the subject of the patent of Anderson, No. 905,728, dated December 1, 1908, the object of my invention being to 15 improve and simplify the construction of the clasp for supporting the globe or shade.

In the accompanying drawing Figure 1 is a vertical section on the line 1—1, Fig. 2, of an electric lamp shade holder embodying my 20 invention; Fig. 2 is a sectional plan on the line 2—2, Fig. 1, showing the clasp in its normal closed position; Fig. 3 is a similar view showing the clasp opened out for the insertion or removal of the shade.

25 In the drawing I have shown my invention as applied to that form of shade holder which is particularly adapted for use on incandescent electric lamp sockets, a screw-threaded part S, Fig. 1, being shown as a 30 part of the means of connection with the socket, but my invention is equally applicable to shade holders or globe supports for gas lamps and the like.

As in the globe support of the Anderson 35 patent, there is a collar or gallery 17 open at the underside for the upward insertion of the neck of the glass globe or shade. Within this gallery is a globe-supporting spring clasp of wire to grasp the neck of 40 the shade or globe. As described in said Anderson patent, this supporting clasp has an inner coil 14 and an outer coil 16, the outer coil being not a complete ring but two ends or arms bearing against the inner 45 face of the gallery. The inner coil 14 has a projecting fold 22, extending through a

guide slot 25 in the gallery, while on the opposite side the outer coil 16 has folds 20 and 21 extending through long guide slots 23 and 24 respectively.

50 My present improvement relates particularly to the construction of the coil ends 16. I impart to each of these coil ends a reverse bend so that each will have two bearing points *x* and *y* to bear against the inner face of the gallery 17 when the clasp is in the closed position shown in Fig. 2, to grasp and support the shade or globe. When by nipping the folds or arms 20, 21 together by the fingers of the hand, the clasp 55 is expanded to permit the withdrawal or insertion of the neck of the shade or globe, as shown in Fig. 3, the ends *y* will still bear against the gallery near the ends of the slots 23 and 24.

60 I claim as my invention—

1. In globe supports, the combination of a gallery with a self-centering spring clasp having an inner coil which grasps the neck of the shade or globe and an outer coil 70 whose ends bear against the inside of the gallery, said outer coil ends having each two points of bearing against the gallery when grasping the shade or globe, substantially as described.

75 2. In globe supports, the combination of a gallery with a self-centering spring clasp having an inner coil which grasps the neck of the shade or globe and an outer coil 80 whose ends bear against the inside of the gallery, said outer coil ends each having reverse bends to afford two points of bearing against the gallery, substantially as described.

85 In testimony whereof I have signed my name to this specification, in the presence of two subscribing witnesses.

JOSEPH E. MARTIN.
